UNITED STATES PATENT OFFICE.

MAURICE J. ROCHE, OF JERSEY CITY, NEW JERSEY, ASSIGNOR OF ONE-HALF TO JOHN A. HARTPENCE, OF TRENTON, NEW JERSEY.

VESTIBULE-CAR CURTAIN-HOLDER.

1,097,469.

Specification of Letters Patent. Patented May 19, 1914.

Application filed January 21, 1914. Serial No. 813,426.

To all whom it may concern:

Be it known that I, MAURICE J. ROCHE, a citizen of the United States, and a resident of Jersey City, in the county of Hudson 5 and State of New Jersey, have invented a new and Improved Vestibule - Car Curtain-Holder, of which the following is a full, clear, and exact description.

This invention relates to improvements in 10 curtain holders, and particularly to curtain holders for vestibule cars, and has for an object to provide an improved structure which may be readily attached and detached, and which will automatically be 15 come detached when a predetermined strain is brought thereon, whereby the curtain is released without tearing.

Another object in view is to provide an 20 improved coupling device for holding the curtains of cars which may have the position thereof varied so that the coupler may be pulled apart after a predetermined strain 25 has been brought to bear thereon.

A still further object in view is to provide 25 a coupling device which may be readily coupled up and readily uncoupled.

In carrying out the objects of the invention the coupling device may be used for coupling any article, as for instance, the 30 curtain of a vestibule car, parts of a chain or other devices, the coupling means being interlocked through the intervention of a sliding sleeve which holds the interlocking portion of the coupler together. When the 35 coupler is used for holding a car curtain in place a sleeve or housing is provided in which a spring is arranged designed to act upon the plunger which is formed with an enlarged coupling or interlocking head. 40 This interlocking head is designed to interlock with a socket member divided into parts. In order to prevent the parts of the socket member from spreading and leaving the head of the reciprocating member a 45 sleeve is provided which is mounted upon a tubular member or housing, which sleeve is adapted to slide over the socket member and thereby hold the same in engagement with the head of the reciprocating member. 50 When a considerable strain is brought to bear upon the socket member the same will move the reciprocating member against the action of the spring until the socket member has passed the sleeve, whereupon the parts 55 of the socket member will open and the head will move back to its original position.

In the accompanying drawings—Figure 1 is a fragmentary sectional view through the abutting ends of two cars, an embodiment of the invention being shown applied thereto; Fig. 2 is an enlarged view of the 60 curtain holder embodying the invention; Fig. 3 is a longitudinal vertical section through the curtain holder shown in Fig. 2, the same being shown on an enlarged scale; Fig. 4 is a 65 detailed perspective view of the socket member; Fig. 5 is a detailed perspective view of the sleeve designed to hold the socket member in place; Fig. 6 is a detailed perspective view of one end of a supporting rod connected to the curtain; Fig. 7 is a plan 70 view of a slightly modified form of the invention to that shown in Fig. 2; Fig. 8 is a detailed fragmentary view approximately on line 8—8 of Fig. 7; Fig. 9 is a sectional view through a slightly modified form of 75 coupler.

Referring to the accompanying drawings by numeral 1 indicates the end of a car and 2 the end of a similar car abutting car 1. The usual bellows 3 and 4 are provided for 80 connecting these cars as the same are of the vestibule type usually found upon Pullmans, and upon other first class cars. In order to cover or hide the bellows 3 and 4, and to make the vestibule structure in keeping with the remaining part of the car a curtain 5 is provided which is connected with car 2, for instance, and is unwound so that the opposite edge will be connected with car 1. Curtain 5 may be of any desired 85 structure and provided with a roller 6 of any desired structure held in place in the usual manner and wound by the usual spring. Connected to the bar 7 of curtain 5 are brackets 8 and 9 which firmly clamp the bar 95 or rod 7, or if desired may pass over part of the curtain 5 so as to clamp the curtain and bar 7 as shown in Fig. 2. The brackets 8 and 9 carry a supporting and guiding bar 10 for socket member 11. The socket member 100 11 is made in parts 12 and 13, part 12 being provided with a bifurcated portion 14, and part 13 being provided with a tongue 15 interlocking, as shown in Fig. 4, and provided with apertures so as to slidably fit over bar 105 10, whereby the socket member 11 may be slid freely up and down bar 10. Each of the parts 12 and 13 is provided with a bored out or hollowed out portion 16 which diverges from the outer end of the members 12 110 and 13 to near the inner end, whereby a

chamber is provided for head 17 arranged on the reciprocating member or plunger 18. The reciprocating member or plunger 18 is threaded at its rear end so as to receive a 5 combined nut and stop 19. Pressing against the nut 19 is a spring 20 which also presses against the shoulder 21 of the sleeve or housing 22, whereby the reciprocating member 18 is given a tendency to remain in an inner 10 position as shown in Fig. 3, but may be readily moved therefrom by bringing spring 20 under compression. It will be evident that by the rotation of nut 19 the constant tension of spring 20 may be varied so as to require a greater or less pull on head 17 to 15 move the same. The sleeve or housing 22 is provided with a guiding bead 23 which is designed to fit into the notch 24 of nut 19 so as to prevent a rotation of nut 19, while in 20 engagement therewith. When it is desired to tighten nut 19 so as to bring spring 20 under constant tension head 17 is depressed so that nut 19 will be moved out of contact with bead 23 and thereby permitted to rotate. Mounted upon the sleeve or housing 25 25 is a tubular member 25 (Fig. 5) which is slidingly mounted upon the casing, and which is adapted to be moved to the position shown in Fig. 3 so as to hold the members 12 and 13 in engagement with head 17. Member 25 is provided with one or more bayonet slots 26 through which suitable 30 guiding pins 27 project, pin 27 being rigidly secured to housing 22. When the sliding tubular member 25 is in the position shown 35 in Figs. 2 and 3 the same is locked against rearward movement, and also holds the socket member 11 in place. When an appreciable pulling strain is brought to bear 40 upon socket 11 the same will move head 17 together with the reciprocating member 18 outwardly against the action of spring 20 until the ends of members 12 and 13 move past the tubular member 25, whereupon 45 members 12 and 13 will separate and the reciprocating member 18 will move back to the position shown in Fig. 2. This is very desirable when the device is used upon cars as the curtain would break in case the cars 50 separated unless the coupler automatically became disconnected. The spring 20 may be brought under any desired tension so that this disconnection or disengagement of members may take place only at a predetermined pull or strain so that small jerks 55 and jars would not in any way affect the holder or coupling device.

In order that the coupling device may adjust itself properly to the movement of the 60 cars the casing 22 is removably secured to the block 28 by any desired means, as for instance by being threaded at 22', as shown in Fig. 3. Block 28 is provided with an aperture through which the journal member 65 29 passes, journal member 29 being arranged

in arms 30 and 31 of member 32. The member 32 is pivotally mounted upon a bolt or securing pin 33 which is connected in any desired manner with a plate 34 secured to one of the cars by any desired means, as for 70 instance screws.

In Fig. 7 will be seen a slightly modified form of the invention in which the casing 22 and associated parts are mounted, as shown in Fig. 3, but the pivotally mounted 75 member 32 is provided with an arm 35 which in turn is provided with a socket 36 designed to be hooked over member 10 or if desired hooked directly over bar 7 so as to hold curtain 5 properly in place even 80 though the socket member 11 was absent. This structure, however, would have the result that the usual fastening means now in use have, namely, the tearing of curtain 5 in case the cars should pull apart. The member 32 in addition to arm 35 is provided with a retaining arm 37 which in turn is formed with a bore 38 containing a reciprocating pin 39 and a spring 40, which tends continually to force pin 39 into suitable 90 apertures provided in plate 4. Pin 39 is provided with a threaded extension which is engaged by a nut 41, whereby upon the rotation of nut 41 pin 36 is removed from either of the apertures 42 in plate 34. When 95 the structure is in the position shown in Fig. 7 pin 39 is in one aperture 42 of plate 34, and when the member 32 is turned until the parts assemble in the position shown in Fig. 3 pin 39 will be moved to the other 100 aperture 42.

In Fig. 9 will be disclosed a further slightly modified form of the invention in which the holder is in effect nothing but a coupler, and may be used for coupling curtains, chains or other devices. In this form of the invention the socket 11 is used but the housing 22 is eliminated. The head 17' is connected with a solid body 43 which may be connected in any desired manner to a 110 chain or to a car so as to act as a coupler. The body 13 is provided with a tubular member or sleeve 25' constructed similar to tubular member 25 shown in Fig. 5. It is to be observed that the difference between 115 this structure and that shown in Fig. 3 is the elimination of the spring 20 and associated parts so that the coupler cannot be pulled apart without breaking or without manually moving the sleeve or tubular member 25' back from the position properly encircling head 17'.

What I claim is—

1. In a curtain holder of the class described, a socket member connected with the 125 curtain, a retaining member connected with said socket member, and means for locking the retaining member and socket member.
2. In a curtain holder of the class described, a socket member connected with the 130

curtain, said socket member being formed with separable parts, said parts having hollowed out portions, a head arranged to fit into the hollowed out portions of said parts, 5 said head merging into a reciprocating member, a spring for manually holding said reciprocating member in a predetermined position, and means engaging said socket for holding said parts in engagement with 10 said head while said spring is holding said head in a predetermined position.

3. In a holder for curtains, a bar connected with the curtain, a socket member slidably mounted on said bar, said socket member being formed with separable parts, a reciprocating member formed with a head fitting into said socket member, means for supporting said reciprocating member, a spring for holding said reciprocating member in a 20 predetermined position, and a sleeve slidably mounted on said means and adapted to be slid over said socket member, whereby said socket member is held in engagement with said head until said head and said reciprocating member are moved a predetermined distance against the action of said spring.

4. A holder for curtains comprising a socket member formed with separable parts, 30 a head interlocking with said parts, a spring acting on said head for holding the same in a predetermined position, and a sleeve for holding said socket member in engagement with said head.

35 5. In a curtain holder of the class described, a socket member connected with a curtain and a retaining member connected with the opposite part to that supporting the curtain, said socket member being 40 formed in parts, said retaining member being formed with a housing, a reciprocating member arranged in said housing formed with a head for fitting into said socket member, a spring acting on said reciprocating member for holding the same in a predetermined position, and a sliding sleeve or 45 tubular member mounted on said housing and adapted to telescope over said socket member a predetermined distance for retaining the socket member in engagement with said head until the socket member has been moved past said sleeve against the action of 50 said spring, whereby the device will automatically become disconnected upon a predetermined strain being exerted thereon.

6. In a holder of the class described, a socket member formed with separable parts, an interlocking member co-acting with said socket member formed with a head projecting 60 into said socket member, and a sleeve mounted to slide on said interlocking member, and to telescope over said socket mem-

ber for holding the socket member in engagement with said head.

7. A curtain holder of the class described 65 comprising a socket member slidably mounted upon a curtain, said sliding connection with the curtain permitting a sliding movement of the socket member, said socket member being formed with separable parts, a reciprocating member co-acting with said socket member, said reciprocating member being formed with a head adapted to project into said socket member, an adjustable stop arranged in the end of said 70 reciprocating member, a sleeve surrounding said reciprocating member for supporting and guiding the reciprocating member, a spring acting against said sleeve and against said stop for normally holding the reciprocating member in a predetermined position, and a sliding member mounted on the housing adapted to telescope over part of said socket member for holding the same in engagement with said head until said reciprocating member has been moved a predetermined 75 distance against the action of said spring.

8. In a curtain holder of the class described, a socket member swingingly and 90 slidably mounted upon the curtain and a retaining member pivoted to a support, the retaining member comprising an arm pivoted directly to said support and a socket interlocking member pivoted to said arm, 95 said last mentioned pivot extending at right angles to said first mentioned pivot, whereby a substantially universal movement is given the retaining member.

9. In a curtain holder of the class described, a pair of clamping members secured to a curtain, a bar supported by said clamping members, a socket member slidably mounted on said bar, said sliding connection with the bar permitting a pivotal 100 movement of the socket member at right angles to the sliding movement, a reciprocating member formed with a head fitting into said socket member, a pivotally mounted casing for supporting said reciprocating 105 member, a spring acting on said reciprocating member for resisting the movement thereof in one direction, and a sliding member mounted on said casing adapted to be moved so as to overlap said socket member and thereby hold said socket member in engagement with said reciprocating member.

In testimony whereof I have signed my name to this specification in the presence of two subscribing witnesses.

MAURICE J. ROCHE.
